HAMMOCK SUPPORT

Louis Carl, Brooklyn, N. Y.

Application May 7, 1947, Serial No. 746,516.

6 Claims. (Cl. 5—129)

1

This invention is a support for hammocks adapted to be used on lawns, porches and other places where trees or other forms of natural supports are not available.

Hammock supports have been heretofore made but they have generally been in the form of continuous tubing bent into elongated parallel portions adapted to rest on the ground and provided at their opposite ends with upstanding loops or inverted V-shaped standards between the apices of which the hammock is hung. These structures are relatively satisfactory in use but they are so cumbersome and bulky that they require excessive space for shipment and storage and can only be transported from place to place with much difficulty.

The object of the present invention is to provide a simple and convenient hammock support which may be dismantled and boxed in relatively small dimensions for shipment but which may be readily assembled for use. The advantages of the present structure are many. It is stronger than any support which I have heretofore seen and it is so constituted that it may be easily packed and taken into the house or garage for storage during the winter. Furthermore, it is so constituted that it may be utilized to support hammocks of different lengths in a thoroughly satisfactory manner.

Speaking generally, the support of this invention embodies a base comprising end sections detachably associated with an intermediate spacer section. The end sections and the spacer sections are preferably rectilinearly adjustable so that the base may be made longer or shorter to fit hammocks of corresponding lengths. Each end section is provided with an upstanding bracket detachably supported on and carrying at its upper end appropriate means for attaching the hammock thereto.

An important feature of this invention resides in ease of assembly of the parts, strength of construction and neatness in appearance.

Features of the invention, other than those specified, will be apparent from the following detailed description and appended claims when read in conjunction with the accompanying drawings.

In the accompanying drawings, I have illustrated different embodiments of the invention but the showings therein made are to be understood as illustrative, only, and not as defining the limits of the invention.

Figure 1 is a side elevation of a hammock support embodying the present invention.

2

Figure 2 is a fragmental perspective, showing one end portion of the base with the corresponding end section disconnected from the intermediate spacer section and the corresponding bracket removed from such end section.

Figure 3 is a fragmental perspective showing the manner in which sections may engage or disengage with the corresponding end of the intermediate spacer section.

Figure 4 is a view similar to Figure 2 but illustrating a modified form of the invention.

Figure 5 is a section on the line 5—5 of Figure 4.

Figure 6 is a section on the line 6—6 of Figures 4 and 5.

Referring first to Figures 1 to 3, inclusive, of the drawings, the reference numerals 1—1 indicate the two end sections and 2 the intermediate spacer section. In the interest of lightness these sections are fabricated from relatively thin channel beams. Both end sections are of identical structure and therefore a description of one will suffice for both. Each end section 1 is formed, as shown best in Figures 2 and 3, by bringing into edge abutting relation the flanges of two channel beams and welding them together so as to form a hollow, rigid, tubular structure. The intermediate spacer section 2 is also formed from channel bars but with the channels to the outside and with these members in parallel relation and spaced apart a distance equal to the thickness of the end section 1, as clearly appears in Figures 2 and 3, so as to permit the end sections to fit between the channels of the spacer section.

The spacing of the channels of the spacer section may be accomplished by welding to these channels transverse plates 3 and transverse pins 4 which have additional functions hereinafter more fully explained. Each tubular end section is transversely slotted on its upper edge as shown at 5 so that when such tubular section is introduced between the channels of the spacer section, after the manner shown in Figure 3, and thereafter the overlapping portions of both sections brought into coincidence with one another, notch 5 will engage with and interfit with the pin 4 while the inboard end of the tubular section will rest upon one of the plates 3 and thus maintain these sections in alignment so as to preclude upthrust of the outboard end of the tubular end section 1. The outboard end of each end section 1 is provided with a transverse foot 6 which may be welded to said section and is of sufficient length to hold this section and the corresponding end of the spacer section in the position shown.

in Figures 1 and 2 against lateral tilting. The foot 6 is also of channel form and is preferably bowed as shown so as to form a firm base on uneven surfaces such as the surface of the ground.

Intermediate the ends of each tubular end section 1 is an upstanding post 7 which may conveniently be let into the flanges of the channels and welded in place in inclined relation to the tubular section so that the posts 7 of the opposite end sections are in the divergent relation shown. These posts 7 are adapted to detachably support corresponding upright brackets 8, each of which is formed of two channels with their flanges brought into edge abutting relation and welded to provide the box-like tubular structure shown. Each bracket 8 has a close sliding fit with one of the posts 7 so as to be readily positioned on or removed therefrom and is provided at its upper end with a hook 9 or other appropriate anchorage for the corresponding end of the hammock H indicated in dotted lines in Figure 1. From the foregoing description of Figures 1 to 3, it will be noted that the end sections may be readily associated with or removed from the spacer section 2 and the inclined brackets 8 may be easily slipped on or removed from the post 7 in assembling or dismantling the device.

In the modified form of construction shown in Figures 4 to 6 inclusive, the spacer section 2a which corresponds to section 2 of the previous figures, is made by bringing flanges of two channels into edge abutting relation and welding them together as shown, while the end sections 1a are made by spacing apart channels with their flanges to the outside and securing them in such spaced relation by pins 4a and spacing plates 3a, so that the spacer section 2a is adapted to be fitted into the end sections instead of receiving same as in the previous figures.

In Figure 4, the spacer section is provided with a plurality of notches 6 spaced apart in the direction of the length of the spacer section and either one or each of these notches may co-operate with the pin 4a to adapt the device to appropriately support hammocks of different lengths.

Figure 5 shows the manner of assembling or dismantling these sections 1a and 2a with respect to one another. Each end section 1a is provided with upstanding post 7 inclined as previously described and secured between the channels of the end section by welding or otherwise. To the outboard end of the end section 1a is welded an upright hollow cylinder 10 and the foot 6a, which corresponds to the foot 6 in the previous figures, is provided with a centrally located rigid stud 11 adapted to extend upwardly through the hollow cylinder 10 and provided in spaced relation above the upper end of the said cylinder with a notched head 12. To one face of the foot 6a, and directly below the space between the channels of the end section 1a, there is welded a locking stop 13, as shown in Figures 5 and 6, and this stop normally projects into the space between said channels to lock the foot in normal transverse relation to said channels. However, because of the spacing between the upper end of the cylinder 10 and the head 12, either end section 1a can be lifted at any time so that the locking stop 13 will clear the lower edge of the end section and permit rotation of the foot 6a into substantially parallel relation to the corresponding end section 1a, to thereby render the structure more compact for packing or storage. The foot 6a is shown as braced by

a gusset bar 14, though this may be omitted without departing from this invention.

The structure of Figures 4, 5 and 6 supports the hammock in the same manner as in Figures 1 to 3 inclusive, but has the advantage that it is adjustable as to length and may be more conveniently adapted for shipment or storage.

Both forms of the present invention are of relatively light construction, easily handled and moved from place to place, yet readily dismantled or assembled when desired. The parts are of strong, rugged construction and will effectively support the hammock even when occupied by very heavy persons or more than one person.

The foregoing detailed description sets forth the invention in its preferred practical form, but the invention is to be understood as fully commensurate with the appended claims.

Having thus fully described the invention, what I claim as new and desire to secure by Letters Patent is:

1. A hammock support comprising: a base composed of end sections detachably secured to the opposite ends of an intermediate spacer section and having upstanding divergent posts and transverse feet to hold said base in upright position, upstanding divergent brackets having detachable telescoped relation with said posts and anchorages at the upper ends of said brackets for attachment of the opposite ends of a hammock thereto, said feet having upright studs extending through bearings in the end sections to permit the feet to be rotated into compact position relative to the end sections, and means for normally locking said feet in transverse position.

2. A hammock support comprising: a base composed of end sections detachably secured to the opposite ends of an interposed spacer section and having intermediate their ends upstanding divergent posts and at their outboard ends an upright cylindrical bearing, a transverse foot positioned beneath the outboard end of each end section and provided with a centrally upstanding stud extending through the corresponding cylindrical bearing to mount the foot for rotation on a vertical axis from a position transverse of the end section to a position substantially parallel thereto and vice versa, means for locking each foot in its transverse position to hold the corresponding end section in upright position, and a bracket having detachable telescoped relation with each upstanding post and provided at its upper end with means for securing one end of the hammock thereto.

3. A hammock support comprising: a base composed of a plurality of successively overlapping sections all of which are formed from channel beams, one of each two overlapping sections having channel beams thereof arranged with their flanges in edge abutting relation and welded together to form a tubular structure and the other having its channel beams spaced apart a distance substantially equal to the thickness of such tubular structure to permit the tubular structure to lie between them, one of each two overlapping sections being provided at its upper and lower edges with stops spaced longitudinally of such section while the overlapping section is provided with at least one notch adapted to engage one of said stops while the end of said section engages the other stop to permit of assembly of the sections when in angular relation to one another and to lock said sections against longitudinal movement when in alignment with

one another, a transverse foot at the outboard end of each terminal section to hold said sections in upright position, upwardly divergent posts each intermediate the ends of each terminal section and brackets detachably telescoped with respect to the said posts and provided at their upper ends with attaching means for the opposite ends of a hammock.

4. A hammock support comprising: end sections composed of a number of parallel bars across the upper edges and adjacent the inboard ends of which is a spacing pin and across the lower edges between the spacing pin and the outboard end of said bars is a spacing stop, said spacing pin and stop both serving to space the inboard ends of said bars apart, an upright cylindrical bearing welded to the outboard ends of each pair of said bars, a foot positioned between the outboard end of each pair of said bars and provided with an upright stud extending through said bearing and provided at its upper end with a head spaced above the upper end of said bearing to mount the corresponding foot for pivotal movement on a vertical axis with respect to each pair of bars, a locking stop carried by each foot and extending between the corresponding bars to normally lock the foot in transverse relation to said bars or to permit of withdrawal from between the bars when the stud is dropped sufficiently for its head to engage the upper end of the bearing, upwardly diverging posts carried by each pair of bars, a bracket having detachably telescoped relation to each of said posts and provided at its upper ends with hammock attaching means, and a spacing section for spacing said end sections apart, the opposite ends of said spacer section being adapted to fit between the bars of the end sections and provided at spaced apart distances along its upper edge and at each end thereof with notches adapted 40

to selectively engage the spacing pin of the corresponding end section.

5. A hammock support comprising: two end sections provided with feet and upright brackets 5 for attachment to a hammock in combination with an intermediate spacer section, each end section having longitudinally and vertically spaced apart stops and each end of the spacer section having notches along its upper edge attached to be selectively engaged with one of such stops of the corresponding end sections while its lower edge engages with the other stop of such end section when the end section and spacer section are in alignment with one another.
